(57) **CLAIM**

The ornamental design for a gua sha device, as shown and described.

DESCRIPTION

FIG. 1 is a front elevational view of a gua sha device, showing our new design;

FIG. 2 is a left side elevational view thereof;

FIG. 3 is a right side elevational view thereof;

FIG. 4 is a rear elevational view thereof;

FIG. 5 is a front perspective view thereof;

FIG. 6 is a rear perspective view thereof;

FIG. 7 is top elevational view thereof; and,

FIG. 8 is a bottom elevational view thereof.

The word "Sugarbear" and the bear ear logo in the Figures are registered trademarks of Besweet Creations Inc.

The broken lines in the drawings depict portions of the gua sha device that form no part of the claimed design.

1 Claim, 8 Drawing Sheets
